UNITED STATES PATENT OFFICE.

JOHN W. EISENHART, OF YORK, PENNSYLVANIA.

POSITIVE SHUTTLE-MOTION FOR LOOMS.

SPECIFICATION forming part of Letters Patent No. 399,138, dated March 5, 1889.

Application filed July 20, 1888. Serial No. 280,549. (No model.)

To all whom it may concern:

Be it known that I, JOHN W. EISENHART, a citizen of the United States, residing at York, in the county of York and State of Pennsylvania, have invented certain new and useful Improvements in Positive Shuttle-Motions for Looms, of which the following is a specification, reference being had therein to the accompanying drawings.

10 This invention relates to that class of looms in which the shuttle is positively moved, and which are designed more particularly for weaving wire fabrics.

15 In the drawings, Figure 1 is a sectional view showing one of the shuttle-operating arms and the frame of the loom in which it is supported, together with the shuttle, in side elevation. Fig. 2 is a sectional plan view of two shuttle-operating arms and adjacent mechanism, said 20 arms being shown in the position assumed when exchanging the shuttle; Fig. 3, a detail perspective view of one end of one of the said arms, showing the shuttle-catch-operating mechanism; Fig. 4, an end view of the shuttle 25 end of one of the arms.

Referring to the annexed drawings, A designates the supporting-frame, in which the shuttle-arms B and C are guided and supported, the latter being reciprocated in any 30 suitable manner by means of the pitmen D. Each arm is preferably square in cross-section and tubular in form, one end being closed by a plug, E, on which is formed an eye, F, for connection with the pitman D.

35 In the plug E is journaled one end of a spring-actuated rock-shaft, G, the said end extending beyond the said plug and carrying a set-collar, H, and an adjustable finger, I. The shaft extends nearly to the other end of 40 the arm, in the interior thereof, or on the exterior, if desired, and is there supported by a block, K, or other suitable bearing, beyond which it carries a cam, L, a lever, eccentric, or equivalent device. To the side of each 45 arm is attached a spring-latch, M, its nose extending through the side of the said arm and carrying a lug, N, to the rear of the said nose and also extending through the arm, suitable slots being provided for the purpose. The 50 cam L is arranged opposite the lug N, so that as it is turned, as hereinafter explained, it will force the latch outward, the resiliency of

the latter returning it when the said cam is moved in the opposite direction.

The shuttle O may be of any suitable construction, with ends formed to enter the arms and provided with notches to receive the noses of the latches.

From the frame A extend offsets P in the direction of the retraction of the arms and to 60 one side of the line of travel, each offset being adjacent to the rear end of the respective arm. Each offset carries a curved dog, R, spring-actuated, and pivotally attached by means of a spindle, S, so as to move on the 65 face of the said offset adjacent to the shuttle-operating arm. The downward movement of the dog is limited by a stop-pin, T, preferably secured to the said dog.

In operation the arms are made to alternately approach and recede, exchanging the shuttle at each forward movement, as is common in machines of this character. The arm carrying the shuttle is caused to reach the central position at a slightly later time than 75 the receiving-arm, for the reason that will presently appear. As the receiving-arm is moved toward the central position, the finger on the rock-shaft will engage the dog R, and, riding over its curved face, will turn the shaft 80 on its axis, moving the cam against the spring-latch, forcing it away from the arm, and when the finger has passed the dog the parts will return to their normal position. Upon a slightly further forward movement the shuttle 85 will be engaged by the latch upon the said receiving-arm, and in the case of the arm carrying the shuttle the finger will ride up on the curved dog to turn the shaft on its axis, moving the cam against the spring-latch and forcing it away from the arm, thus releasing the 90 shuttle and allowing the receiving-arm to recede before the finger drops over the curved dog, and the latch be thus returned to its normal position. When the arms are retracted, 95 the fingers will pass under the dogs, the latter moving out of the way without turning the shaft.

In Fig. 2 the arm C has received the shuttle, having moved a sufficient distance forward for the finger to be relieved from the dog and the latch to engage the shuttle, and has commenced the backward movement, while the arm B, which carried the shuttle to

the center, advancing more slowly than the other arm, has not had the finger released from the dog; hence the shuttle is withdrawn before the spring-latch falls. This operation 5 is alternately repeated by each arm.

As it is evident that the above description, when taken in connection with the drawings, would suggest modifications of the device to a skilled mechanic, I do not limit myself to the 10 precise construction and arrangement of parts described, as the same may be modified without departing from the spirit of my invention.

I may employ any suitable means for operating the pitmen D D—such, for instance, as 15 that shown in United State Patent No. 365,420, granted June 28, 1887, to J. Widmer. The dog or curved arm R is held in its normal position, as shown in Fig. 3, by means of a small coiled spring, a, surrounding the pin S and 20 suitably secured. The rock-shafts G are returned to their normal positions, after the fingers I drop off of the inner ends of the dogs R, by means of the spring-catches M, the lugs N on these catches being kept normally 25 pressed against the inclined periphery of the cams L by means of the resiliency of the catches.

Having thus fully described my invention, what I claim as new, and desire to secure by 30 Letters Patent, is—

1. In a positive shuttle-motion for looms, the combination, with a reciprocating shuttle-operating arm, of a latch for engaging the shuttle, and carried by the arm, a rock-shaft 35 also carried by the arm and provided with a cam or equivalent device for moving the latch, and means, substantially as described, for operating the shaft.

2. In a positive shuttle-motion for looms, the combination, with a reciprocating arm, of 40 a latch on the arm for engaging the shuttle, a rock-shaft carried by the arm and provided at one end with a cam or equivalent device and at the other end with a finger, and a dog arranged in the path of the said finger to operate the said shaft, substantially as described. 45

3. The combination of a frame, the reciprocating tubular carrier-arms mounted in this frame, spring-latches upon the inner ends of these arms for engaging the shuttle, rock- 50 shafts journaled inside of these tubular arms and provided with cams on their inner ends for operating the shuttle-latches, adjustable fingers on the outer ends of the said rock-shafts, means for adjusting these fingers, and 55 pivoted dogs for operating the said rock-shafts and fingers, substantially as described.

4. The combination of a frame, reciprocating carrier-arms, spring-latches carried by these arms, rock-shafts carried by these carrier-arms and provided on their inner ends with cams for operating the said spring-latches, fingers on the outer ends of these rock-shafts, curved dogs R, pivoted to the 60 said frame in line with the said fingers, and 65 springs for keeping these dogs normally pressed downward, substantially as described.

In testimony whereof I affix my signature in presence of two witnesses.

JOHN W. EISENHART.
